DESIGN FOR A DRESS

Morris Kaufman, New York, N. Y.

Application November 14, 1938, Serial No. 81,067

Term of patent 3½ years

To all whom it may concern:

Be it known that I, Morris Kaufman, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the dress disclosed of the specific stitching arranged on the blouse and sleeves in the manner and position shown.

I claim:

The ornamental design for a dress, substantially as shown and described.

MORRIS KAUFMAN.
